WAGON DRILL

Albert Feucht, Cleveland, Ohio, assignor to The
Le Roi Company, Milwaukee, Wis., a corpora-
tion of Wisconsin

Application May 10, 1948, Serial No. 26,121

5 Claims. (Cl. 255—51)

1

This invention relates broadly to rock drills, but more particularly to a drilling rig generally known in the art as wagon drill.

One object of this invention is to produce a wagon drill wherein the rock drill or drilling motor is adapted to remain substantially over the wheels supporting its frame when moved within a wide range of different drilling positions, thereby maintaining the major weight of the drilling motor and of its supporting structure within or above the supporting frame and preventing upsetting of the wagon drill as well as facilitating its movement from one drilling location to another.

Another object of this invention is to produce such a wagon drill wherein the drilling motor is readily accessible and movement of the operator about the drilling motor is not encumbered by supporting braces as heretofore provided in drilling apparatus of this type.

Another object of this invention is to produce a wagon drill, wherein the drilling motor may be moved into any desired position through a simple and efficient mechanism requiring little effort on the part of the operator.

Other objects and advantages more or less ancillary to the foregoing and the manner in which the various objects are attained, reside in the specific construction and aggroupment of the elements peculiar to this structure, as will become apparent from a more complete examination of this specification, in the claims of which there are assembled certain specific constructions indicative of the scope and spirit of the invention.

In the drawings which illustrate the invention:

Figure 1 is a side elevational view of the wagon drill embodying the invention. In this figure, the drilling apparatus is shown in perpendicular relation with its supporting frame.

Figure 2 is a view corresponding to Figure 1 but showing the drilling apparatus in substantially parallel relation with its supporting frame and located below the latter.

Figure 3 is a top plan view of the wagon drill with the drilling apparatus in the position shown in Figure 2.

Figure 4 is an enlarged sectional view taken through planes indicated by line 4—4—4 in Figure 1.

Figure 5 is an enlarged sectional view taken through planes indicated by line 5—5—5 in Figure 1.

Figure 6 is an enlarged sectional view taken

through a plane indicated by line 6—6 in Figure 3.

Figure 7 is an enlarged cross sectional view taken through one side member of the supporting frame in a plane indicated by line 7—7 in Figure 1 and looking in the direction of the arrows. In this figure a portion of the housing has been broken away to show details of construction.

Figure 8 is a view similar to Figure 4, shown in a somewhat reduced scale with portions of the mechanism broken away and extended to illustrate both sides of the main frame and the closed end of the drill supporting frame.

Referring to the drawings in which like symbols designate corresponding parts throughout the several views, 10 represents the main frame of the wagon drill which is substantially U-shaped with two side members 11 and 12 united by a cross member 13. On the free end of each side member is secured a bracket 14 which operatively supports a frame carrying wheel 15. Also secured to the cross member 13 at equal distances from its ends is a bracket 16 which operatively supports a caster wheel 17 and a handle 18.

Carried by the main frame for movement relative thereto as will hereinafter be explained, there is a substantially rectangular drill supporting frame 9 which includes two parallel side members 19 and 20 united at one end by a cross member 21, which members, like those of the main frame, are preferably made of tubing sections welded together. The drill supporting frame is narrower than the main frame and made 35 to pass freely through the open end and between the side members of the latter. As shown in Figure 8, the other end of the drill supporting frame is also closed by a tubular cross member 22 which is welded to the end of the side members 19 and 20 and extends beyond them to end substantially above the side members 11 and 12 of the main frame where the ends of the cross member 22 are carried through two identical connections, one of which is clearly shown in Figure 4. As part of these connections, each end of the cross member 22 is accurately machined to form a shafted portion 23, ended by a flange 24, which portion is rotatably supported within the head 25 of a bracket 26. Integral with the bracket's head 25, there are two longitudinally spaced substantially U-shaped clamps 27 which straddle the side members of the main frame. Each clamp 27 carries a cross pin on short shaft 28 on which is rotatably mounted a roller 29 for engagement with the underside portion of the side

members of the main frame 10. Above the center axis of the drill supporting frame cross member 22, the bracket's head 25 is provided with a semi-circular inwardly tapered seat 30 which extends about 30° on each side the vertical passing through its longitudinal axis. Thereafter the tapered seat is cut-off to provide a recessed semi-circular flat portion 31, which portion as seen in Figures 4 and 8 is located primarily below the center axis of the drill supporting frame cross member 22 while the seat 30 is located above it. Engaging the tapered seat 30, there is a relatively thick correspondingly tapered washer 32 which has its inner end wall provided with a raised portion or step 33 engaging the flat portion 31 of the bracket's head 25. The distance between the center axis of the tapered seat 30 and that of the rollers 29 is calculated to cause the washer 32 to engage the upper portion of the side member of the main frame while the rollers engage the under portion thereof. Extending through the drill supporting frame cross member 22 as well as through the bracket's head 25 and washers 32, there is a long bolt 34 having its head resting against the outer wall of one of the washers 32 between stops 35 provided thereon to prevent its rotation. The free end of the bolt is adapted to receive a nut 36 which has a cylindrical shoulder 37 resting against the other washer 32 between its stops 35.

Intermediate its ends but closer to the cross member 22 than the cross member 21, each side member 19 and 20 of the drill supporting frame has rigidly secured thereto a trunnion 38 which extends laterally and outwardly relative to said frame and has pivotally mounted thereon one corner 39 of a bell crank brace or lever 40 through which the drill supporting the frame may be raised or lowered relative to the main frame 10 as will be hereinafter explained.

Rigidly secured to each side members 11 and 12 of the main frame 10 but closer to its open than its closed end, there is a trunnion 41 located below the side members 11 and 12 and extending laterally and inwardly relative to the main frame in parallel with the trunnions 38. On each trunnion 41 is pivotally mounted the second corner 42 of the bell crank lever 40.

The third corner 43 of each bell crank lever 40 is also equipped with a pivotal connection which may broadly be referred to as a trunnion 44 which is parallel to the other two but extends outwardly from the lever 40 to end above the side members of the main frame as clearly shown in Figure 5. On each trunnion 44 there is mounted a spacer 45 held in position by a washer 46 and nut 47, on which spacer is pivotally mounted the clevis end 48 of a relatively long stationary screw 49 secured to the clevis 48 by a set screw 50.

The screw 49, for the major portion of its length, is covered by a tube 51, also secured to the clevis 48 by the set screw 50. Mounted on the screw 49 in operative engagement therewith, there is a cylindrical nut 52 having welded thereto one end of a torsion tube 53, which is free to rotate and move longitudinally over the screw 49 and within the tube 51 to form therewith a telescopic cover or seal for the screw. The torsion tube 53 extends through the free end of the tube 51 and has welded or otherwise affixed to its other end a journal 54.

Near the closed end of the main frame 10, each side member thereof has welded thereto an upwardly extending bracket 55 which has piv-

totally secured to the upper end thereof by a bolt 56 a worm and gear housing assembly 57. As shown in Figure 6, the housing 57 operatively carries two spaced ball bearings 58 in which the journal 54 or end portion of the torsion tube 53 is rotatably supported. Between the two bearings 58 the journal 54 carries a worm gear 59 rigidly secured thereto by a key 60, which gear is in mesh with a worm 61 rotatably mounted within ball bearings 62 accommodated within the upper end of the housing 57. Each worm 61 extends transversely of the main frame 10 and has its inner end extending through the housing 57 as clearly shown in Figure 3 and Figure 7 and are rigidly connected to each other by a connecting rod or shaft 63. The outer end of the worm 61 also extends through the housing 57 but outside of the main frame 10 where it is appropriately shaped to receive a handle 64 through which the worms 61 may be rotated manually.

Secured to the cross member 21 of the drill supporting frame by a conventional saddle 65, there is a boom or drill guiding frame 66 on which is slidably mounted the fluid actuated drill 67 and drill steel 68 extending from the front end thereof. Since the saddle 65, drill guiding frame 66 and drill 67 form no part of this invention, no further description is thought necessary other than pointing out that the conventional saddle 65 affords a connection between the drill carrying frame and drill guiding frame whereby the former may be moved and secured in about any desired position relative to the latter. It is also to be understood that in constructions of this type, the drill guiding frame 66 accommodates a feeding mechanism through which the drill 67 may be power fed in both directions on the frame 66.

In the operation of this improved wagon drill, it will now be understood that the drill carrying frame which includes the two side members 19 and 20 may rigidly be secured to the main frame 10, by tightening the nut 36 (Figures 4 and 8) in the bolt 34 and causing the washers 32 to be forced inwardly on the taper seats 30 of the brackets 26. The hole through each washer is made large enough to enable lateral movement of the washer relative to the bolt 34. Since the inward movement of each washer is limited by the engagement of its shoulder 33 with the flat portion 31 of the bracket's head 25, further inward axial pressure exerted on the washers by the tightening of the nut 36 will cause the taper seats 30, cooperating with the tapered sides of the washers, to act as cams for driving the washers downwardly into engagement with the upper wall of the side members of the main frame. This downward movement of the washers will result in each bracket 26 being clamped on its corresponding side member of the main frame between the washer 32 and the rollers 29, thereby preventing longitudinal movement of the drill supporting frame relative to the main frame. Once the washers 32 are in clamping relation with the side members of the main frame, further tightening of the nut 36 will cause clamping engagement of the washers with the taper seats 30 to prevent pivotal movement of the drill supporting frame relative to the main frame. Thus it will be understood that through the simple manipulation of one single nut, the drill supporting frame may be locked to the main frame against both pivotal and longitudinal movements relative thereto.

In order to facilitate longitudinal movement of

the drill supporting frame relative to the main frame, each bracket 26 has been provided with two rollers 29 in operative engagement with the under side of the side members of the main frame. Because of the location of the connections between the supporting frame side members 19 and 20 with the bell crank levers 40 together with the relatively heavy weight of the drill guiding frame 66 and drill 67 carried by the cross member 21, when the nut 36 is loosened the drill guiding frame will tend to cause upward movement of the brackets 26 relative to the main frame, which upward movement is checked by the rollers 29 engaging the undersides of the side members 11 and 12 of the main frame without hindering the longitudinal movement of the drill supporting frame relative to the main frame.

The pivotal and longitudinal movements of the drill supporting frame relative to the main frame is effected concurrently by manually rotating the crank or handle 64 for imparting rotation to the two worms 61 connected to each other by the connecting rod 63. From the worms 61 rotation is imparted to the two worm gears 59 at the same rate of speed and therefrom transmitted to the nuts 52 through the journals 54 and torsion tubes 53. Since the nuts 52 are in operative engagement with the stationary screws 49, their rotation will effect either expansion or retraction of the telescoping tubes 51 and 53 and the consequential pivotal movement of the bell crank levers 40 on their pivots 42 through which the levers are connected to the main frame 10. This pivotal movement of the bell crank levers will cause one end of the drill supporting frame to slide on the main frame while its other end, that is the end carrying the drill guiding frame 66, moves up or down within one substantially vertical plane passing through the center axis of the wheels 15.

Should it be desired to move the drill guiding frame 66 from the position shown in Figure 1 to that shown in Figure 2, after the nut 36 has been loosened, the crank 64 would be rotated to impart pivotal movement to the bell crank levers 40 around the pivots 42 in a clockwise direction in Figure 1. In this instance, this rotation would be effected by a retraction of the telescopic braces between the brackets 55 and the corners 43 of the levers 40. Because of this pivotal movement of the bell crank levers 40, the lower end of the drill supporting frame (Figure 1) will slide on the side members 11 and 12 of the main frame 10 toward the brackets 55, while the upper end of the drill supporting frame will be moved below the side members 11 and 12, enabling the drill guiding frame 66, which had previously been shifted from a vertical to an horizontal position, to be located close to the ground as clearly shown in Figure 2.

It is an important feature of this invention to locate the pivot 42 of the bell crank levers 40 on the main frame 10 to assure, together with the length of the sides of the bell crank levers and the length of the supporting frame, position of the drill guiding frame or its center of gravity substantially above the axis of the wheels 15. Through the bell crank levers and their appertinent connections, the drill guiding frame 66 may be moved up and down relative to the main frame 10 while remaining substantially above the center axis of the wheels 15, thereby enabling adjustment of the drill guiding frame to any desired drilling position without danger of upsetting the entire wagon drill. Furthermore, since the cen-

ter of gravity of the drill guiding frame remains substantially above the wheels 15, the entire wagon drill can readily be moved from one drilling location to another.

5 Although the foregoing description is necessarily of a detailed character, in order to completely set forth the invention, it is to be understood that the specific terminology is not intended to be restrictive or confining and it is to be further understood that various rearrangement of parts and modification of structural detail may be resorted to without departing from the scope or spirit of the invention as herein claimed.

15 I claim:

1. In a wagon drill, a wheel supported main frame, a drill supporting frame, connecting means between said frames including a connecting element slidable on said main frame and a pivot between said element and drill supporting frame enabling concurrent longitudinal and pivotal movements of the drill supporting frame relative to the main frame, a bell crank lever, a first pivotal connection between said lever and main frame, a second pivotal connection between said lever and drill supporting frame, a gear mechanism carried by said main frame, a pair of screw threaded telescopic elements extending from said mechanism toward said lever, connecting means between one of said elements and mechanism capable upon operation of the latter of imparting rotation to the former for effecting telescopic motion of said elements, and a third pivotal connection between said lever and the other of said elements, said lever and connections being arranged and disposed in a manner effecting said concurrent movements upon telescopic motion of said elements.

2. In a wagon drill, a wheel supported main frame, a drill supporting frame, connecting means between said frames including a connecting element slidable on said main frame and a pivot between said element and drill supporting frame enabling concurrent longitudinal and pivotal movements of the drill supporting frame relative to the main frame, a bell crank lever, a first pivotal connection between said lever and main frame, a second pivotal connection between said lever and drill supporting frame, a rotation imparting mechanism carried by said main frame, a pair of screw threaded elements extending from said mechanism toward said lever telescopically movable upon rotation of one element relative to the other, rotation transmitting means between said mechanism and said one element, and a third pivotal connection between said lever and the other of said elements, said first pivotal connection being fixed on said main frame to cause pivotal movement of said lever thereon upon telescopic motion of said elements, said concurrent movements being effected by virtue of said second pivotal connection and the pivotal movement of said lever.

3. In a wagon drill, a main frame formed with an open end, supporting wheels for said frame adjacent the open end thereof, a drill supporting frame carried by said main frame, connecting means between said frames enabling one end of said drill supporting frame to be raised and lowered relative to said main frame substantially within a vertical plane passing through the center axis of said wheels, including a connecting element slidable on the main frame and a pivot between said element and drill supporting frame, a bell crank lever having a first pivotal connec-

tion with said main frame and a second one with said drill supporting frame, said lever being pivotable by virtue of said first connection for effecting movements of the end of said drill guiding frame within said vertical plane, a rotation imparting mechanism carried by said main frame, a pair of screw threaded elements extending from said mechanism toward said lever telescopically movable upon rotation of one element relative to the other, rotation transmitting means between said mechanism and said one element, and a third pivotal connection between said lever and the other of said elements for effecting pivotal movement of said lever upon telescopic movement of said elements.

4. In a wagon drill, a substantially U-shaped main frame, supporting wheels for said frame adjacent the open end thereof, a secondary frame carried by said main frame having a drill supporting end, a connecting element slidable on said main frame and a pivot between said element and secondary frame enabling concurrent longitudinal and pivotal movements of said drill supporting end through the open end of said main frame, a trunnion carried by said main frame between the open end thereof and said connecting element, a bell crank lever pivotally carried by said trunnion, a pivotal connection between said lever and secondary frame adapted to swing around said trunnion during pivotal movement of said lever for effecting said concurrent longitudinal and pivotal movements, a rotation imparting mechanism carried by said main frame near the closed end thereof, and means connected to said lever and mechanism having rotation imparted thereto from the latter for effecting pivotal movement of the former.

5. In a wagon drill, a wheel supported main frame, a drill supporting frame, connecting means between said frames including a connecting element slidable on said main frame and a pivot between said element and drill supporting frame enabling longitudinal and pivotal

5 movements of the latter frame relative to the main frame, a bell crank lever pivotally connected to said main frame, a pivotal connection between said lever and drill supporting frame whereby pivotal movement of said lever on said main frame effects longitudinal and pivotal movements of said drill supporting frame, a rotation imparting mechanism carried by said main frame, a pair of screw threaded elements extending from said mechanism toward said lever telescopically movable upon rotation of one element relative to the other, rotation transmitting means between said mechanism and said one element, another pivotal connection between said lever and the other of said elements effecting pivotal movement of said lever upon telescopic movement of said elements, and locking means carried by said connecting element operable for preventing longitudinal and pivotal movements of said drill supporting frame.

15 20 25 30 35 40 ALBERT FEUCHT.
